UNITED STATES PATENT OFFICE

GEORGE RUSSELL GOFF, OF HOPEDALE, MASSACHUSETTS, ASSIGNOR TO DRAPER CORPORATION, OF HOPEDALE, MASSACHUSETTS, A CORPORATION OF MAINE

BOBBIN AND BOBBIN CLUTCHING SPINDLE

Application filed November 6, 1929. Serial No. 405,134.

This invention relates to that type of spinning apparatus in which a rotatable spindle having a plurality of centrifugally-acting clutching members is employed. In this type of apparatus the rotation of the bobbin with the spindle is secured by the radial pressure of the clutching members against the wall of the bore in the butt of the bobbin. When starting and stopping the spindle the frictional pressure thus exerted is insufficient to secure the desired rotation of the bobbin with the spindle.

The object of the present invention is to provide a construction in which a positive driving engagement will take place between the clutching members and the bobbin whenever there is any rotary slippage between the bobbin and the spindle.

Such a positive driving connection was broadly provided in the construction disclosed in the patent to Draper, No. 760,973, May 24, 1904, but in that case the clutching members acted directly against the material of the bobbin itself which was commonly wood, and the positive driving connection was secured by a metal pin or by a configuration of the wood of the bobbin.

In the present invention a metal bushing is provided which is secured in place in the bore of the butt of the bobbin and this bushing is so constructed as to afford the desired positive driving engagement with the clutching members. By this means the rotary equilibrium of the mass of the bobbin and the spindle under all conditions is not disturbed whether the driving engagement between the clutching members and the bobbin be purely frictional or partly frictional and partly positive and all danger of disturbance of equilibrium by wear of the bobbin is prevented.

The nature and objects of the invention will appear more fully from the accompanying description and drawings and will be particularly pointed out in the claim.

The invention is applicable to any type of spinning apparatus in which a rotatable spindle having a plurality of equally-circumferentially-spaced centrifugally-acting clutching members is employed and for pur-

poses of illustration the construction of spindle shown in the pending application of Wallace I. Stimpson, No. 380,256, filed July 23, 1929, is illustrated.

In the drawings:

Fig. 1 is a view in side elevation of the main portion of the spindle and in vertical cross section of the lower portion of the bobbin embodying a preferred form of the invention.

Fig. 2 is a view on a larger scale with all the parts excepting the spindle blade shown in vertical cross section.

Fig. 3 is a view in perspective of one form of metal bushing embodying the invention.

The spindle illustrated comprises the usual blade 1 with the whirl 2 rigidly secured thereto. The upstanding portion 5 of the whirl at its upper face is provided with the concentric recess 4 and is covered by an annular cap 5 having a driven fit thereon and presenting at its upper face the bobbin seat 6. The clutching members 7 are each of similar construction and are equally spaced circumferentially about the spindle, being here shown as four in number. Each clutching member is here shown as fulcruming at 8 directly on the spindle blade 1. Each clutching member at its lower end is shown as having a radial outwardly projecting foot 9 located in the recess 5 and at its upper end a fin 10 extending within the retaining and spacing cap or sleeve 11 secured to the spindle blade. These clutching members rock outwardly under the influence of the annular spring 12 surrounding and resting upon the feet 9. These members are also heavily weighted above the fulcrum points so as to be subject to a substantial centrifugal force when the bobbin is rotating at the usual speed.

In this invention the bore 13 of the bobbin has secured therein, as by a driving fit, a metal bushing 14, a preferred form of which is shown separately in Fig. 3. This bushing is of such a diameter that normally the clutching member 7 will be pressed by the spring 12 and by centrifugal action against the inner surface 15 thereof to effect the drive of the bobbin from the spindle.

In order to secure the desired positive driv-

ing engagement between the spindle and the bobbin whenever there is any slippage, this bushing is provided with similar recesses 16 and similar ribs 17 intervening between the recesses 16. These recesses and ribs may take any desired form, but in the preferred construction the recesses 16 are formed as slots extending through the metal of the bushing while the ribs 17 are formed by the material of the bushing extending between the slots. The ribs 17 thus broadly constitute projections as compared radially with the slots or recesses 16.

The similar recesses 16 are equally-circumferentially-spaced and each recess is of a width not less than the width of the corresponding clutching members, such as 7, so that when a clutching member swings radially outward opposite a recess, it may project into the recess. The number of the recesses 16 must be an aliquot or a multiple of the number of the clutching members in order to prevent any disturbance of the equilibrium of the bobbin and spindle mass. For example, in the case illustrated, there are two recesses 16, which is an aliquot of the four clutching members 7 illustrated, the recesses being, therefore, spaced apart a distance which is greater than the width of the respective recesses.

It will thus be seen in the operation of the mechanism that if any slippage takes place between the spindle and the bobbin, at least one pair of similarly disposed bobbin clutching members drops into one pair of similarly disposed recesses in the bushing and at once effects a positive driving engagement therewith, the leading edges of the bobbin clutching members engaging the edges of the recesses or the edges of the intervening ribs.

It is of greatest importance that the equilibrium of the bobbin and spindle mass shall not be disturbed. Otherwise the bobbin and spindle will vibrate when rotating at high speed and uneven spinning of the yarn will result. In this invention the equilibrium is maintained under all conditions and the positive driving engagement is secured whenever there is any slippage. Furthermore there is no danger of the equilibrium being disturbed as the result of wear because the clutching members under all conditions cooperate with the metal of the bushing.

The clutching members are cammed inwardly by the metal bushing when the bobbin is placed in position and they are also cammed into the recesses whenever rotary slippage takes place between the spindle and the bobbin so that metal surfaces, subject to a minimum wear, are always co-acting whenever a relative movement takes place between the bobbin and the spindle.

Having thus described the invention, what is claimed as new, and desired to be secured by Letters Patent, is:

The combination of a rotatable spindle

having a plurality of symmetrically located, centrifugally acting clutch members, with a bobbin having a metal bushing in a bore in the butt thereof, said bushing having a plurality of symmetrically located recesses circumferentially spaced to cooperate with certain of said clutch members only to form a positive driving connection with the bobbin through the said metal bushing, the clutch members located between the said recesses frictionally engaging the bushing to thereby center the bobbin on the spindle.

In testimony whereof, I have signed my name to this specification.

GEORGE RUSSELL GOFF.
